HEATING SYSTEM

Milton A. Powers, Detroit, Mich., assignor to The Timken-Detroit Axle Company, Detroit, Mich., a corporation of Ohio

Application November 4, 1944, Serial No. 561,980

1 Claim. (Cl. 237—8)

1

The present invention relates to gravity flow heating systems and more particularly to combined space and domestic hot water heating systems.

It is a major object of this invention to provide a novel combined space and domestic hot water heating system wherein said space is heated only after the domestic hot water reaches a predetermined temperature, and the space heating portion of the system is a gravity and convection flow arrangement wherein relatively cool return water is admixed and entrained with outgoing relatively hot water from the boiler so as to provide passage of a relatively large amount of rather moderately heated water through said space heating portion so that the latter is heated slowly and uniformly and without waste or excessively high temperature conditions.

A further object of this invention is to provide a heating system having novel and improved means for effecting recirculation of the fluid.

Another object of the invention is to provide a heating system having a fluid circulating loop in which adjacent parts of the supply and return conduits have communicative connection for recirculation and in which one of said parts is equipped with means for facilitating entrainment of the cooler return fluid with the outgoing hotter supply fluid.

A further object of the invention is to provide a heating system having a domestic water heating loop in by-pass relation with a space heating loop and novel temperature responsive means operative to automatically control the flow of fluid through the respective loops.

A still further object of the invention is to provide a heating system of the aforesaid character which operates at high efficiency with gravity flow.

Further objects will become apparent as the specification proceeds in connection with the annexed drawings, and from the appended claims.

In the drawings:

Figure 1 is an elevational view of a preferred embodiment of the system of the invention having parts diagrammatically illustrated therein;

Figure 2 is an enlarged detailed section through a part of the system;

Figure 3 is a section taken substantially on line 3—3 of Figure 2;

Figure 4 is an enlarged side elevational view of another part of the system partly broken away to illustrate interior construction; and

Figure 5 is a section taken on line 5—5 of Figure 4.

Referring to the drawing by reference characters in which like characters designate like parts, 10 designates each of a plurality of space heating means such as room heating radiators having the inlet side connected, through branch pipes 12,

2

with a supply conduit or header 14 supported in a substantially horizontal position. The outlet of each radiator is connected, through a return branch 16, with a substantially horizontal return conduit or header 18. Connected to the supply header, as by a T 20, and depending therefrom, is a riser conduit generally indicated at 22. Connecting with an upper part of the riser 22, through a T 24, is an essentially horizontal conduit 26 constituting a supply main having its opposite end connected to the outlet of a boiler 28, of any desired construction. To the inlet of boiler 28 is connected one end of a horizontally extending conduit 30 having its other end connected with a bottom part of the riser 22, as by a reducing T 32, to the bottom of which latter is connected a drain pipe 34.

A conduit 36 connects the return header 18 with the riser 22 at a point below and adjacent the junction of supply main 26 with riser 22 and may embody a T 38 connecting a horizontal run of conduit 36 with the riser in close proximity to the T 24. Thus, riser 22 embodies a section 40 between T 38 and the return conduit or main 30, a section 42 between T 24 and the supply header 14, and a quite short section or nipple 44 between the T fittings 24 and 38.

A domestic water heater, generally indicated at 46, is mounted vertically between and has fluid communicative connection with the supply and return mains 26 and 30. Heater 46 is advantageously of the indirect type having a central tube 48 extending axially through a vertical tank 50. The lower end of tube 48, extending below the bottom closed end of the tank, connects with the return main 30 through a T 52 while the upper end of the tube, extending through the closed top end of the tank, connects with the supply main 26 through the medium of a fitting generally indicated at 54. Cold water is supplied to the tank 50 by a feed pipe 56 while hot water for tapping and other domestic purposes is drawn therefrom through a pipe 58.

Water from a suitable source of supply is delivered to the boiler 28 through a pipe 60 making connection with the boiler through a branch pipe 62 and with a pipe 64, connecting the boiler with a compression tank 66, through a T 68. As is customary, line 60 may be equipped with a pressure reducing valve 70 and a pressure relief valve 72, also acting as a blow-off for the compression tank.

The fitting 54, which is illustrated in detail in Figures 4 and 5, embodies a T 92 having one horizontal outlet formed with a flange 94 bolted to a matching flange 96 on one end of a tubular valve housing 98. Between the flanges 94 and 96 is clamped the peripheral margin of a partition plate 99 having a central opening 100 leading into a pocket 102. The sides of pocket 102

are provided with transversely aligned openings 104 and 106, at the edges of which are formed annular seating bosses 108 and 110. In guide bearings 112 and 114, supported centrally of the openings 104 and 106 by spiders or other suitable means, is mounted a transversely disposed axially slidable valve stem 116, having fixed on opposed end portions valve disks 118 and 120. These disks are mounted so that at one position of axial travel of the stem they seat upon the respective bosses 108 and 110 to close the side openings of the pocket while, in reverse position of the stem, they assume open position. To a pin 122 supported vertically between projections on the plate 99 is fixed the inner end of a temperature responsive element 124, such as a spirally coiled bimetallic strip. The outer end of the strip 124 is connected fixedly to the valve stem 116. An arm 128 fixed to and extending radially from the pin 122 engages the lower end of a regulating spindle 126 operable by a hand wheel 130 secured on the upper end thereof to turn arm 128 for calibrated adjustment of the strip 124. The opposed outer ends of the T 92 and housing 98 threadedly connect with spaced parts of the supply main 26 while the downwardly directed outlet of T 92 connects with the upper end of the heater tube 48.

The thermostatic element 124 is mounted in fitting 54 substantially in the zone of intersection between the vertical and horizontal runs 26 and 48 and is designed to so operate that, when there is no demand for heat in the radiator loop and the domestic heater 46 is supplied from the boiler with heating fluid below a predetermined temperature under control of thermostatic element 84, the control valve within fitting 54 is held closed and there is no flow in main 26 beyond fitting 54. This is sufficient to heat the hot water in tank 50 to desired temperature for direct domestic use.

When the boiler is supplying heating fluid to main 26 at a higher temperature than that predetermined temperature under control of thermostat 86 in response to demand for heat to the space heated by the radiators, and the hot water in tank 50 is at or above its desired temperature, the control valve in fitting 54 is opened by thermostatic element 124 to supply heat to the radiators. Upon decrease of the temperature of the water in tank 50, as when hot water is drawn off at a faucet, there is a resulting lowering of the heating fluid temperature in the zone about thermostat 124 and the latter operates to cause partial or complete closing of the supply control valve, depending upon the extent of temperature drop of the water in the tank. After the water in tank 50 has been raised to the desired temperature, excess heat accumulates in the T chamber of the fitting 54 to eventually raise the temperature of the heating fluid in the zone about thermostatic element 124 to cause opening of the control valve, so that flow of heating fluid through main 26 to the radiator loop is resumed. Specifically, when the temperature of the heating fluid in the T 92 is in excess of that required to bring the domestic hot water to its desired temperature, thermostatic element 124 expands sufficiently to actuate stem 116 and move valve disks 118 and 120 to open position to enable flow of heating fluid to the radiators. Should the heating fluid temperature within the T 92 fall, either because of demand for heat by the domestic heater or lowering of the temperature of the boiler output under control of the thermostat 84, the element 124 will contract and seat

the disks and cut off flow of heating fluid to the radiators.

The T fitting 24, as illustrated in Figures 2 and 3, is equipped with a deflector 132 fixed therein so as to direct the fluid entering from the supply main 26 upwardly at one side of the T while providing a passage 134 behind the deflector for entrainment of part of the return fluid entering T 38 from the return conduit 36. The element 132 may be in the form of an angular plate having a lower part 136 extending diagonally upward from the shoulder between the bottom and lateral outlets, to the center of the T and has a web 138 rising from the top edge of the diagonal part along the axis of the vertical run. As illustrated in Figures 2 and 3 the element 132 provides a restriction in the heating fluid supply main, and resultant increased velocity of flow therethrough increases the entrainment of the cooler return fluid.

The boiler 28, for example a conventional hot water boiler, is heated by any preferred heating means such as an oil burner indicated 74. The oil burner 74 is equipped with known switch means electrically connected, through conductors 76, 78 and 80, in parallel with a thermostatic member 84, constituting a device responsive to the temperature of the water in the boiler, and a space or room thermostat 86, to line wires 38 and 90.

Under conditions wherein there is no demand for heat in the space heated by the radiators 10, the thermostatic member 84 functions to maintain the water of the boiler 28, and consequently the water in the domestic supply tank 50, at an approximately constant desired temperature, below that at which the control valve in fitting 54 is set to open. In the event that the temperature in the space heated by the radiators should fall to a predetermined degree, the burner control circuit through the thermostat 86 is closed with the result that the boiler water is heated to a temperature above the maximum permitted by thermostat 84 to provide required excess heat for radiators. When the temperature in the space heated by the radiators rises to a predetermined maximum the control circuit through the thermostat 86 is broken. If there should be no demand for heat to the radiators for extended periods of time, the consequent lowering of the temperature in the boiler will result in automatic closing of the control valve in fitting 54 and the domestic hot water supply at 50 will be maintained under the control of thermostat 84.

During the gravity and convection circulation through the radiator plant of the system, the heating fluid supply flows from the boiler through a loop comprising the supply main 26, T 24, upper section 42 of the riser, header 14 and the radiators. The return flow is effected through return header 18, return conduit 36, lower section 40 of the riser and the return main 30 to the boiler. As the hot water from the boiler flows through the T 24, the element 132 serves to deflect the relatively high speed flow thereof to one side and upwardly, creating injector action in passage 134 of the T and causing entrainment and intermixing of parts of the cooler return fluid entering T 38 from the return conduit 36 with the outgoing hot water supply. The hotter the supply fluid, the greater its velocity and the larger the amount of cooler return fluid which will be entrained therewith. As a result of such intermixing, a relatively large quantity of fluid at a temperature lower

than that at the boiler discharge is circulated through the radiators, effecting gradual heating throughout the radiator system as contrasted with the relatively greater temperature variation and unbalanced heat distribution that would be produced by higher temperature supply of water in less volume. Thus when supplied with heating fluid each radiator gradually rises in temperature and all rooms receive their desired share of the total heat from the boiler. Without this feature, the relatively high temperature of the water entering the space heating system upon opening of the thermostatic valve and the fact that the volume of such flow is limited by the heating capacity of the boiler may result in a portion of the radiators becoming highly heated while others receive little or no heat.

The connection of the indirect heater 46 between the supply and return mains forms a bypass loop constantly open to the boiler outlet and return. This insures prompt and efficient indirect heating of the water in the storage tank at all times when there is heated water in the boiler.

Likewise the positioning of the thermostatic valve control element in this constantly open loop connection to the boiler at a point above the storage tank insures prompt and effective control of the flow of excess heated water to the radiators whenever the temperature exceeds the setting of valve adjustment.

The system is advantageous in that a constant supply of hot water for domestic use is continuously available, regardless of the space heating requirements. Furthermore under all conditions likely to be encountered, the system functions automatically to maintain or re-establish hot water in the domestic storage tank. At any instant, only excess heat beyond that which the tank is able to absorb is allowed to flow to the radiators, thus insuring maximum speed in re-establishing the reserve supply of hot domestic water. For example, let us consider a cold day, with the total boiler output going to the radiators, the domestic storage tank having been fully heated. There is a sudden excessive drain on the domestic hot water supply and it is exhausted. The replacement of the hot water in the tank by cold water surrounding the tube 48 will cause the water in that tube to cool, and hot water from boiler main 26 will immediately flow through tube 48 to reheat the domestic water. However, the radiators were already using the entire capacity of the boiler. Consequently the temperature of the water in the zone around the thermal element drops somewhat, the valve partly closes to reduce the flow to the radiators, and the heat flow to the storage tank increases. This condition prevails until the water in the storage tank is reheated, at which time the full flow to the radiators is reestablished.

Consider now that the entire system is cold, and both domestic water and radiator heat are suddenly demanded. The unrestricted water loop between boiler and domestic water tank insures prompt heating of the tank to the maximum capacity of both boiler and tank. This will continue until the tank is heated at which time the thermal valve will open to allow all heat to flow to the radiators. As the tank gains heat, its absorbing capacity falls away and whenever excess heat is available the thermal valve will send such excess to the radiators.

Other conditions of operation might be described, but those given will serve to illustrate

the fact that my system is so designed as to assure an ample domestic water supply under all conditions, regardless of the space heating requirements.

5 The invention may be embodied in other specific forms without departing from the spirit or essential characteristics thereof. The present embodiment is therefore to be considered in all respects as illustrative and not restrictive, the 10 scope of the invention being indicated by the appended claims rather than by the foregoing description, and all changes which come within the meaning and range of equivalency of the 15 claims are therefore intended to be embraced therein.

What is claimed and desired to be secured by United States Letters Patent is:

In a heating system, a boiler, a space heating plant having a supply header and a return header 20 connecting with a plurality of radiators or like heat dissipating means, a riser having its upper end connecting with said supply header, a supply main having one end connected with the boiler outlet and having a substantially horizontal run 25 connected with an elevated part of the riser, a substantially horizontal return main connecting a lower part of the riser with the boiler inlet, a domestic hot water storage tank having a heater conduit therefor connected between said supply main and said return main in bypass relation 30 to said space heating plant, a temperature responsive valve in the connection between said supply main and said heater conduit for proportioning flow of boiler water to said space heating plant and said domestic hot water storage tank and permitting flow of hot water to said space heating plant only when said water temperature exceeds a predetermined value, a conduit 35 connecting said return header with the lower part of the riser and immediately adjacent the junction of the supply main with said riser and at a substantial distance above the return main so that fluid returning from said heat dissipating means flows from said return header down the 40 lower part of said riser and through said return main into the boiler, and flow deflecting means 45 mounted in said junction of the supply main with the riser adapted to deflect all of said supply fluid from said supply main upwardly through 50 said riser in such manner as to cause entrainment therewith of part of the cooler fluid flowing into the riser from the return header.
